UNITED STATES PATENT OFFICE.

ASA J. HARWOOD, OF RICHMOND, INDIANA, ASSIGNOR TO THE ATLAS UNDERWEAR CO., OF PIQUA, OHIO, A CORPORATION OF OHIO.
UNION UNDERGARMENT.

1,177,700.

Specification of Letters Patent.

Patented Apr. 4, 1916.

Application filed July 13, 1915. Serial No. 39,537.

To all whom it may concern:

Be it known that I, ASA J. HARWOOD, a citizen of the United States, residing at Richmond, in the county of Wayne and State of Indiana, have invented certain new and useful Improvements in Union Undergarments, of which the following is a full, clear, and exact description, such as will enable others skilled in the art to which it appertains to make and use the same.

This invention relates to undergarments and more particularly to union suits of the drop-seat type for men's wear.

One of the objects of the invention is to provide an improved union undergarment which may be constructed with an economy of material and at a reduced manufacturing cost.

Another object is to provide a simplified drop-seat union suit comprising a minimum number of parts and embodying various features enhancing the comfort, convenience and serviceability of the garment in use.

A further object is to create a commercially practicable drop-seat union suit having characteristics of structural superiority and functional advantage.

Other objects and advantages will be in part obvious and in part noted hereinafter in connection with the accompanying drawings which illustrate a typical embodiment of the invention.

In the drawing, Figure 1 is a front elevational view of a union undergarment; Fig. 2 is a rear elevational view of the same; Fig. 3 is a side view of a tubular knitted blank in an initial stage of manufacture; Fig. 4 is a rear view thereof folded at right angles to Fig. 3; Fig. 5 is a front view of the same; and Fig. 6 is an elevational view of one part of the garment.

The garment illustrated comprises, in general, a unitary association of body and lower limb portions having a normally closed posterior opening and a longitudinal anterior opening enabling the suit to be donned. These openings are not continuous but are preferably separated by an intermediate closure consisting of a part of the seat portion provided to afford requisite fullness where desired and to overlie the posterior utility opening.

Referring more specifically to the drawings, the union suit illustrated comprises

a body 1 and legs 2 of integrally knitted or woven material or other suitable fabric. Arms 3 and collars 4, as well as suitable cuffs and anklets, may be provided if desired. The body 1 is centrally slitted at 5 and provided with faced reinforced edges to overlap and fasten by buttons 6 or other means permitting ready separation and attachment of the sides when the garment is invested. The anterior opening 5 preferably terminates at 7 slightly above the horizontal plane of the crotch *a*, *a*, and above the upper ends of the leg in-seams. The rear of the garment is provided with a wide opening 9 arched from its sides 10 and 11 and converged therebelow to points 12 and 13 on the inner leg seams beneath both the point 7 and the plane of the crotch.

A separate and one-piece seat 14 of uniform knitting or weave is provided as a closure for the rear opening 9 and for affording requisite fullness to this portion of the garment. The seat 14 is attached to the rear of the body at points 15 and 16 slightly above and beyond the sides of the posterior opening and is stitched from thence along the converging lower edges of said opening to points 13 and 12 of the leg seams, where an extension of added fullness of the seat curves forward and upward to the point 7, being stitched to the edges of the front leg material. An upper and tapered flap 17 of the seat overlaps the body material above the opening 9 and is attached thereto by a pair of buttons or the like. It will be apparent that by unfastening and dropping the seat flap 17, the posterior opening 9 of relatively large dimensions becomes exposed. Furthermore, the seat provides, in effect, a gore between the leg portions of the garment and gives a comfortable fullness in the seat and crotch. Also, as will be hereinafter described more in detail, the piece 14 provides an anterior fullness 19 centrally offset and adjacent the crotch which renders the garment of increased comfort in use and allows left dress, as will be understood.

Referring more particularly to the second sheet of the drawings, there is shown an integrally knitted or woven tube 20, constituting a blank from which the body and legs of the garment are formed. In practice, the blanks 20 are cut in multiple; that is a plurality of the same are folded flat and superposed so that several of the garments

may be cut at a single operation. The lower corners of the blanks are severed at the front (the left in Fig. 3) from 21 to 22, and at the rear from 23 to 24. A cut is also made to provide the posterior opening 9, this cut extending from the rear leg cut at 24, curving upward into the body portion, to 25, and arching outward from 10 adjacent 25 to the rear edge of the folded blank, at 26. A short central slit 27 is also cut at this time in the upper end of the blank for arm-holes. The tubular units are then operated and refolded flat at right angles to the first fold into the form of Figs. 4 and 5, respectively, rear and front views, prior to stitching. At this time, or before, a central slit 28 is also cut into the body. The seat pieces 14 are similarly cut in piles and according to a flat pattern shown in Fig. 6, that is, of substantially rectangular shape with the upper corners tapered and having a curved slit or shearing 29 in the lower edge offset from the center. More specifically, the location and dimension of the slit 29 is such that the lower edges of the piece 14 from the corner 30 to point 31 equals the remainder of the edge 31, 32 to 33.

The seat piece 14 is sewed to the body of the garment in the manner above described; that is, the lower part of the seat is stitched with edges 15—30 and 16—33 applied to body edges 25—24 and 25'—24' to the inseams of the legs, and with edge 30—31 to front leg edge 24—22 and edge 33—32—31 to the opposite front leg edge 24'—22. The loose material of the seat between points 30 and 33 thus provides a gusset in the garment crotch with all seams off-centered so that the crotch is formed of smooth, unstretched fabric whereby frictional irritation or binding is effectually eliminated in this region. Furthermore, as above indicated, the material of the seat at the full side of slit 29 folds to provide a centrally offset pocket or fullness 19 in front of and adjacent the crotch. The garment is thus, in effect, of the full-fashioned type, that is, conforming in general to the human form, and this result is attained without altering the knitting or weave of the body or seat, or stretching the same in any part.

The provision of the cuts 25—10 and 25'—11 in the body adjacent the posterior

opening facilitates the stitching thereto of the corresponding edges of the seat pieces 55 and materially reinforces the seam at this point. Furthermore, when the seat flap 17 is dropped, the strain as the parts are separated, falls equally on the entire transverse length of the seams from 25 to 10 and 25' to 11, so that any liability to tearing or disconnection at these points is obviated. Also when the flap is buttoned to close the rear opening, a substantial overlap of the entire arched upper edge of the opening is attained. A complete closure is thus effected and without any tendency of the parts to fold or wrinkle with attendant discomfort to the wearer. The tapered formation of the flap also allows the use of but two fastening buttons, which facilitates manipulation thereof when desired.

Having described my invention, what I claim as new and desire to secure by Letters Patent is:—

1. A drop-seat union undergarment comprising suitable body and leg portions, and a drop-seat portion closing the crotch and providing an anterior centrally offset fullness adjacent the crotch.

2. A drop-seat union undergarment comprising, in combination, a tubular body portion having a cut-away posterior opening arched upward from points adjacent its sides and having outward and upward extending severances from said points, and a seat portion having straight edges stitched to the edges of said severances and thence toward the crotch and having a drop flap thereabove to overlie the arched edge of said posterior opening.

3. As an article of manufacture, a union undergarment drop seat substantially rectangular in shape and having a centrally offset oblique severance in its lower edge, said severance being so located and of such dimension that the longer lower edge of said seat substantially equals in length the remainder of said lower edge together with the edges of said severance.

In testimony whereof I affix my signature, in the presence of two witnesses.

ASA J. HARWOOD.
